UNITED STATES PATENT OFFICE.

ARTHUR EUGENE BERUBÉ, OF ST. THOMAS, ONTARIO, CANADA.

COMBINED COLLAR BUTTON AND CRAVAT-RETAINING DEVICE.

Application filed October 27, 1925. Serial No. 65,250.

My invention relates to improvements in combined collar button and cravat retaining devices and the object of the invention is to devise a collar button which will not only serve to hold the collar together and to the band of the shirt but also serve to hold the knot of the tie up in position after it has been adjusted to the collar.

My invention consists of a collar button having a suitable base, a stem projecting therefrom, an end crossbar provided with upwardly extending prongs, preferably two in number, the button being otherwise constructed as hereinafter more particularly explained.

Figure 1 is a view of the collar with the button fastening it together and projecting through the button holes.

Figure 2 is a cross sectional detail showing the manner the knot of the tie is held in position on the collar button.

Figure 3 is a front elevation of the button.

Figure 4 is a plan and

Figure 5 is a side elevation.

In the drawings like characters of reference indicate corresponding parts in each figure.

1 is a collar which is provided with opposing flaps having the usual button holes, 2 and 3.

4 is the band of the shirt having the usual button hole 5.

6 is my collar button as provided with the usual base, preferably round, and having an outwardly extending stem 7 in which is fastened the crossbar 8 having upwardly extending prongs 9, preferably two in number.

It will, of course, be understood that the tie will be placed in position around the collar, if it is of the type shown, without being tied. The collar button is previously inserted in the hole 5 of the shirt band, the collar is then placed in position by inserting and pulling the button holes over prongs 9 and onto stem 7. The tie is then tied in a knot and such knot is drawn up tight to the top of

the collar and then pulled down slightly so that the prong 9 extends into the knot of the tie.

It will thus be seen that the tie will be held securely in position as will also the collar itself the knot of the tie serving to hold the collar button securely in place in the button hole and likewise the prongs help to hold the knot in place as hereinbefore intimated.

Although I think the crossbar 8 with double bars 9 is a preferable construction for the reason that the knot will be held from canting in either direction. It will of course be understood that the stem may be made with a single prong. When wing collars are used the invention is equally applicable but in this case it will not be necessary to put the tie on the collar before the collar is buttoned over the collar button.

From this description it will be seen that my collar button is of the simplest construction, will not wear the button holes as ordinary collar buttons will and effectually not only retain the collar in place from unbuttoning but also the tie itself. It may also be used with a bow tie.

What I claim as my invention is:

1. A combined collar button and cravat retaining device comprising a base, a stem extending outwardly therefrom and provided at its outer end with bifurcated portions having an upwardly extending spicular projection at the outer end of each of such portions.

2. A combined collar button and cravat retaining device comprising a base, a stem extending outwardly therefrom and provided at its outer end with bifurcated portions forming a crotch like portion acute angular in form and adapted to receive the central portion of the tie, and a spicular projection extending outward from the extremity of each portion at each side of such crotch to enter the tie at each side of the aforesaid central portion.

ARTHUR EUGENE BERUBÉ.
